(57) CLAIM

The ornamental design for a pen clip eraser and holder, as shown and described.

DESCRIPTION

FIG. 1 is a perspective view of a pen clip eraser and holder showing my new design;

FIG. 2 is an end elevational view, the opposite end elevational view being a mirror image thereof;

FIG. 3 is a top view thereof; and,

FIG. 4 is a bottom view thereof.

The broken lines showing environment in FIG. 1 are shown for illustrative purposes only and form no part of the claimed design.
